UNITED STATES PATENT OFFICE.

CHARLES L. SHEPPY, OF BUFFALO, NEW YORK, ASSIGNOR TO THE PIERCE-ARROW MOTOR CAR COMPANY, OF BUFFALO, NEW YORK.

CARBURETER.

1,213,914.

Specification of Letters Patent. Patented Jan. 30, 1917.

Application filed August 6, 1912. Serial No. 713,677.

To all whom it may concern:

Be it known that I, CHARLES L. SHEPPY, a citizen of the United States, residing at Buffalo, in the county of Erie and State of New York, have invented a new and useful Improvement in Carbureters, of which the following is a specification.

This invention relates more particularly to that type of carbureters for internal combustion engines which are provided with

one or more supplemental nozzles for increasing the supply of fuel in the explosive mixture as the speed of the engine increases.

With the ordinary carbureters having a single fuel discharge nozzle, it is extremely difficult, if not impossible, to obtain an explosive mixture of correct proportions of air and gasoline for all engine speeds, especially in the case of engines having a

considerable range of speed. The mixture is not rich enough for high speeds and it is too rich for low speeds. Attempts have been made to overcome this difficulty by

providing a supplemental fuel discharge nozzle which is brought into action either manually or automatically by the increasing suction as the engine speeds up. The manually controlled carbureters are objectionable because they are not automatic and

require hand adjustment for different speeds. The carbureters heretofore made in which the action of the supplemental gasoline nozzle is dependent upon the suction of the engine, are open to various practical objections. In those in which an auxiliary air valve is arranged between the supplemental gasoline nozzle and the throttle valve, a perceptible period of time elapses between the opening of the auxiliary

air valve and the commencement of the discharge of gasoline by the supplemental nozzle, and this arrangement results in an imperfect and undesirable action of the carbureter. The proportion of gasoline in the

mixture is too high until the auxiliary air valve opens, and the mixture is then diluted or weakened until the supplemental nozzle starts to discharge and correct the error.

When the supplemental nozzle starts to discharge, the proportion of gasoline is suddenly increased and the mixture remains too heavy until the speed of the engine is considerably increased. Thus the regulation of

the mixture is not in strict accordance with the gradually varying demands due to the

increasing speed of the engine. In other prior constructions the auxiliary air valve and supplemental fuel nozzle are so constructed and arranged as to cause a sudden objectionable increase in the air and fuel supply instead of the gradually increasing supply necessary to the successful operation of motors having a considerable range of speed.

The object of this invention is to produce a thoroughly practical and efficient carbureter having main and supplemental fuel supply nozzles which will operate automatically so as to insure an explosive mixture of proper proportions at all speeds of the engine, and in which the main fuel nozzle can be adjusted to supply a small enough amount of fuel to produce good running at slow speeds, the supplemental nozzle being relied upon to supply the additional fuel necessary for faster speeds. This is accomplished by providing the carbureter with a main fuel nozzle which is located in the main air inlet passage and supplies the fuel for slow speed running, and a supplemental fuel nozzle which is located between the auxiliary air valve and the throttle valve, preferably at a higher level than the main nozzle, and comes into action to supplement the supply from the main nozzle only when the suction of the engine is great enough to open the auxiliary air valve.

In the accompanying drawings consisting of two sheets: Figure 1 is a sectional elevation in line 1—1, Fig. 2, of a carbureter embodying the invention. Fig. 2 is a sectional elevation thereof in line 2—2, Fig. 1.

Like reference characters refer to like parts in the several figures.

A represents the constant level gasoline or float chamber of the carbureter, B the valve actuated by an annular float C in the float chamber for controlling the level of gasoline in the float chamber, D the main air inlet passage; E the main gasoline supply nozzle located in a contracted portion of the air inlet passage and communicating by passages e with the float chamber, e' the adjustable needle valve of the nozzle, F the auxiliary air inlet passage controlled by the auxiliary air admission valve G, H the air and gasoline mixing chamber to which the main and auxiliary air inlet passages lead and which connects by a discharge passage I with the engine, and K

the throttle valve, located between the gasoline nozzles and the discharge passage I, preferably in the mixing chamber H. While these parts are preferably constructed and arranged as shown in the drawings and, with the exception of the auxiliary air valve, are substantially the same as disclosed in United States Patent No. 943,242, granted Dec. 14, 1909, to Fergusson and Sheppy, assignors, this construction is not necessarily essential to the invention and the parts could be of other suitable construction and arrangement.

The auxiliary air valve preferably consists, as shown, of two or more spring strips or reeds *g* controlling slots or openings *g'* in the walls of an inclosing casing. These reeds have different degrees of resiliency, so that they are opened one after another as the suction increases and thus effect a gradual admission of the air.

g² are spring tongues for limiting the opening movement of the reeds. The admission openings are surrounded by a fine 25 mesh screen *g³* for preventing the entrance of dust.

L represents the supplemental gasoline or fuel nozzle which is connected by a suitable passage *l* with the float chamber and is arranged with its discharge orifice at a point between the auxiliary air admission valve and the throttle valve, preferably in the auxiliary passage F, and at a suitable elevation above the discharge orifice of the main 35 nozzle E. The discharge from this nozzle is controlled by an adjustable needle valve *l'* which for convenience passes upwardly through the carburetor casing and is provided at its upper end with a head for turning it.

l² indicates a spring detent engaging the serrated head of the needle valve for releasably holding it in adjusted positions.

The supplemental nozzle can be constructed and arranged between the auxiliary air valve and the throttle valve in any suitable way, and any suitable regulating valve, therefore, can be used.

When the engine is running slowly the auxiliary air valve remains closed and the air passes up through the main air inlet passage D past the main gasoline nozzle E, so that the gasoline is caused to flow forcibly from this nozzle by the suction and mixes with the air as it passes through the throttle valve and mixing chamber in the usual manner. As the throttle valve is opened wider and the engine speeds up, the increased suction opens the auxiliary air valve and air is taken in through this valve and the passage F above the main nozzle. This greater suction, together with the action of the air in flowing through the passage F past the supplemental nozzle, draws gasoline from this nozzle, in addition to that being supplied

by the main nozzle E, thereby furnishing the increased quantity of gasoline required for higher speeds of the engine. This arrangement enables the supply from the main nozzle to be adjusted small enough to insure good running at slow speeds, the supplemental nozzle serving to supply the additional gasoline necessary for faster speeds. By reason of the described location of the supplemental nozzle between the throttle valve and the auxiliary air admission valve having a plurality of admission ports which are opened one after another as the suction increases, the supply of gasoline is increased gradually in accordance with the increasing speed of the engine, and the mixture will not be too rich for some speeds and too lean for others.

I claim as my invention:

1. In a carburetor, the combination of a liquid fuel chamber, means for maintaining a substantially constant fuel level therein, a main fuel supply nozzle arranged in a main air supply passage and connected with said fuel chamber, a plurality of auxiliary air admission valves which are opened in succession by the suction of the engine with which the carburetor is connected, a supplemental fuel supply nozzle arranged in the path of the air admitted by said auxiliary air valves, said supplemental fuel nozzle being connected at its inlet end only with said fuel chamber and adapted to discharge fuel only, the discharge end of said supplemental fuel nozzle being at a higher elevation than that of the main fuel supply nozzle and constantly open, and a throttle valve located between both of said fuel nozzles and the discharge passage of the carburetor for controlling the mixture from both of said fuel supply nozzles.

2. In a carburetor, the combination of a liquid fuel chamber, means for maintaining a substantially constant fuel level therein, main and auxiliary air supply passages, a fuel nozzle arranged in the main air supply passage and connected with said fuel chamber, a plurality of valves which control the admission of air to said auxiliary air passage and are opened in succession by the suction of the engine with which the carburetor is connected, a supplemental fuel supply nozzle connected at its inlet end only with said fuel chamber and adapted to discharge fuel only, the discharge end of said supplemental fuel nozzle being located in said auxiliary air passage and at a higher elevation than the discharge end of the main fuel supply nozzle and constantly open, adjustable means for regulating the maximum discharge of said supplemental fuel nozzle, and a throttle valve located between both of said fuel nozzles and the discharge passage of the carburetor for controlling the mixture from both of said fuel supply nozzles.

3. In a carbureter, the combination of a liquid fuel chamber, means for maintaining a substantially constant fuel level therein, a fuel supply nozzle arranged in a main air supply passage and connected with said fuel chamber, a plurality of auxiliary air admission valves consisting of independently movable spring strips of different tensions which are opened in succession by the suction of the engine with which the carbureter is connected, a supplemental fuel supply nozzle arranged in the path of the air admitted by said auxiliary air valves, said supplemental fuel nozzle being connected at its inlet end only with said fuel chamber and

adapted to discharge fuel only, the discharge end of said supplemental fuel nozzle being at a higher elevation than that of the main fuel supply nozzle and constantly open, and a throttle valve located between both of ²⁰ said fuel supply nozzles and the discharge passage of the carbureter for controlling the mixture from both of said fuel supply nozzles.

Witness my hand this 29th day of July, ²⁵ 1912.

CHARLES L. SHEPPY.
